COMBINED HIP AND BODY HARNESS

Theo J. Sowle, Grand Rapids, Mich.

Application March 28, 1956, Serial No. 574,422

8 Claims. (Cl. 2-2)

This invention relates to protection harness for football players and, in particular, to hip and body protection harness.

Hitherto, the bodies and hips of football players have been protected by separate protection harnesses or pads. The upper portion of the player's body has been protected by so-called blocking pads or rib-and-kidney protectors which have been hung by straps from the shoulders, whereas the hips have been protected by hip protector pads strapped around the waist of the player. As a result, when the player bent over, the adjacent edges of the rib-and-kidney protector and hip protector moved apart from one another, opening up a gap in the most vulnerable place in the player's body, namely in the region of the kidneys, exposing the lumbar region and the upper portions of the hip bones and iliac crest. Consequently, crippling injuries have frequently occurred in the use of these separate rib-and-kidney protectors and hip protectors. Moreover, youthful players have frequently worn their hip protectors or hip pads low on their hips like a cowboy's chaps, accentuating the evil by completely uncovering the kidney region and wholly failing to give it any protection. As a consequence, blows against the player's back in the gaps thus created and upon the vital regions thus exposed have resulted in serious injuries to youthful players and caused agitation against the playing of football itself.

In the invention shown in my co-pending application Serial No. 511,287 filed May 26, 1955 for Combination Hip and Body Harness, now Patent No. 2,805,418, granted September 10, 1957, I have disclosed and claimed a combined hip and body harness which is adaptable to the different positions of the body assumed in playing the game of football, yet all the while affording protection to all vital regions of the hips and body. That invention provides a combined hip and body harness wherein the hip protector or pads serve as a foundation upon which the rib-and-kidney protector or body pads are supported by upstanding supports at the opposite sides of the body, with the result that shoulder straps with their attendant defects of twisting, discomfort, inelasticity and pulling-up of the pads are eliminated, the tops of the hip bones, lumbar region and the tip of the iliac crests are never exposed and crippling injuries consequently cannot occur, as in the past. That harness of that invention, however, while very satisfactory in a given size for a correspondingly-sized player, must be made in different sizes for players with different lengths of torso, as not being adjustable for different lengths of torso.

The principal object of the present invention is to provide a combined hip and body harness of the foregoing character which can be adjusted to the different lengths of torso of different players yet which still gives full protection to the player himself.

Other objects and advantages of the invention will become apparent during the course of the following description of the accompanying invention, wherein:

Figure 1 is a front elevation of a combined hip and body harness according to one form of the invention, with the body of the player shown in dotted lines;

2

Figure 2 is a side elevation of the combined hip and body harness of Figure 1, with the body of the player also shown in dotted lines;

Figure 3 is an enlarged vertical cross-section through the interconnecting and supporting structure of the harness of Figures 1 and 2, taken along the lines 3-3 in Figures 2 and 4; and

Figure 4 is an enlarged rear elevation of the interconnecting and supporting structure shown in Figure 3, taken along the line 4-4 therein.

Referring to the drawings in detail, Figures 1 and 2 show a combined hip and body harness, generally designated 10, for football players or the like as consisting generally of a padded hip protector 12 having adjustable upstanding supporting and connecting structures 14 on opposite sides thereof, preferably of a semi-rigid material, and supporting a padded girdle-shaped body or rib-and-kidney protector 16 on the upper ends thereof. The hip protector 12 is shaped to fit the hip region H of the torso T and for that purpose is curved outwardly and downwardly to form a rearward guard portion 18 conforming to the bulge of the buttocks B. The hip protector 12 is also provided with side guard portions 20 on the opposite sides thereof, these being separated from one another at the front by an upwardly-arched indented or cutaway portion 22 (Figure 1) and separated from the rearward guard portion 18 by upward indentations 24 located therebetween (Figure 2). Each of the side guard portions 20 at its upper region has an upwardly-curved iliac crest protecting portion 26 which has an arched top edge portion 27, and a downwardly-curved or upwardly-arcuate forward upper edge portion 28 at the free ends 30 of the side guard portions 20. The iliac crest protecting portion 26 has a rearward upper edge portion 32 which curves downwardly and rearwardly toward the back upper edge 34, which is approximately horizontal (Figure 1) and which joins the two opposite side guard portions 20 at the rear.

The hip protector 12 near the lower ends of the side guard portions 20 is provided with hip pads 36 of semi-rigid material which is resistant to blows (Figure 2), and the iliac crest protecting portions 26 are similarly provided with iliac pads 38 of similar material and similarly designated to protect the top of the hip bones or iliac crests. A belt 40 encircles the hip protector 12 at a location between the iliac pads 38 and hip pads 36 above the bulge of the buttocks B where at the location 42 the rearward guard portion 18 is convex. The forward ends or free ends 44 and 46 of the belt 40 are adjustably interconnected by a buckle 48.

Each upstanding supporting and connecting structure 14 includes a flexible lower strap 54 of leather, textile webbing or other suitable material having its lower end 52 secured as by the stitches 50 to the portion 26 near the upstanding upper edge 27 thereof. The lower strap 54 extends inwardly over the edge 27 (Figure 3), then downward around the lower edge 56 of a vertical supporting plate 58 of fiber, plastic or other stiff material, then upward along the rear surface thereof through a lower slot 60 and terminates in an upper end 62 provided with perforations 64. The upper end 62 of the lower strap 54 is connected as by the lacing 66 to perforations 68 in the lower end 70 of an upper strap 72 of material similar to that of the lower strap 54. The upper strap 72 proceeds upward along the front surface of the plate 58, thence through an upper slot 74 therein, thence upward along the rearward surface thereof and over the upper edge 76 of the plate 58, thence downward along the front surface of the plate 58, and thence around the arched lower edge 78 of the forward side member 80 of the rib protector 16 to which it is secured by stitches 82.

The forward side member 80 of the rib-and-kidney protector 16 in the region adjacent its lower edge 78 is preferably of fiber, as is the portion 26, and is connected by multiple parallel straps 82 to a rearward side member 84 of similar construction to the forward side member 80 but of opposite configuration. Each of the forward side members 80 has a constricted front end 86 or 88, the former terminating in a strap 90 and the latter carrying a buckle 92 receiving the strap 90 (Figure 1). Immediately adjacent the constricted front end portions 86, the forward side members 80 are provided with downwardly-extending portions 94 (Figure 1) which give further protection to the front of the body, particularly the lower ribs. The upper edges 96 of the forward and rearward side members 80 and 84 curve upward and rearward at a slightly inclined angle (Figure 2) to the spaced rearward vertical edges 98 of the latter. Vertically-spaced parallel horizontal reinforcement or strengthening bars 100 are mounted in the front quarter portions in order to strengthen these members and provide additional protection for the ribs of the wearer. The forward and rearward side members 80 and 84 have spaced adjoining vertical edges 102 and 104 (Figure 2) respectively, interconnected by a gusset 106 of elastic material such as elastic webbing, which is stitched or otherwise secured there-to.

In the use of the invention, to put on the combined hip and body harness 10, the player unfastens the upper and lower buckles 92 and 48, places the hip protector 12 around his hips and the rib protector 16 around his ribs and the adjacent portion of his body, and refastens the buckles 92 and 48. The lower buckle 48 is fastened in a comparatively snug manner so that the hip protector 12 rests firmly upon the hips and buttocks of the player without the possibility of sliding down. The upper buckle 92, however, is fastened somewhat more loosely so that the body or rib-and-kidney protector 16 fits that portion of the player's body comparatively loosely and thereby provides flexibility of motion and adaptability of fit between the upper and lower protectors 15 and 12 respectively, as well as between the protectors and the player's torso T.

When the combination harness 10 has thus been put on, and adjusted and fastened in the above manner, the player is completely protected as regards his vital organs and bones, regardless of what position he assumes, whether standing, crouching, kneeling or bending in any direction. The upstanding semi-rigid supporting plates 58 provide articulation between the upper and lower protectors 16 and 12 so as to afford relative motion there-between while protecting the vital areas of the body and preventing the opening up of any gap which would expose any such vital area to injury from blows. The upwardly-extending iliac protecting portions 26, the iliac pads 38, and the upstanding supporting plates 58 also provide complete protection to the iliac crests or tops of the hip bones, thereby preventing the injuries thereto which have frequently occurred notwithstanding the provision of prior hip and body pads because of the lack of protection afforded thereby. Such injuries have frequently crippled players and inflicted permanent damage to their bodies.

The ribs or bars 100 give additional protection to the player's ribs and viscera, yet the material of the upper or rib protector 16 is flexible and compressible in such a manner as to enable it to compress when the player leans forward, causing the ribs 100 to come closer together. The flexible connection afforded by the straps 54 and 72 and the upstanding supporting plates 58 gives the player the facility of twisting his body or moving sidewise, forward or backward, with relative motion between the upper and lower protectors 16 and 12, yet giving complete protection at all times to the spine and other vulnerable portions of the body.

If the player has a long torso, the upper or rib-and-kidney protector 16 is moved upward relatively to the

lower or hip protector 12 by tightening the lacings 66 (Figures 3 and 4) and retying them in a shortened state. This action causes the strap ends 62 and 70 of the lower and upper straps 54 and 72 to be pulled toward one another through the lower and upper slots 60 and 74, thereby raising the lower edge 56 of the supporting plate 58 and at the same time raising the lower edge 78 of the side portion 80 of the upper or rib protector 16. In this manner, the edges 27 and 70 (Figure 3) are spaced vertically farther apart from one another, lengthening the torso adjustment, yet the overlapping arrangement of the plate 58 at its lower and upper ends still provides complete protection at the player's opposite sides between the upper and lower protectors 16 and 12.

To adapt the harness 10 to a player with a shorter torso, the reverse procedure is followed. In other words, the lacing 66 is loosened and retied in a lengthened condition, so that the strap ends 62 and 70 are spaced more widely apart from one another. This, in effect, lengthens the working portions of the straps 54 and 72, thereby permitting the lower edge 78 of the upper protector 16 to move downward toward the upper edge 27 of the lower protector 20. The result is that the gap between these edges 78 and 27 is narrowed, and the harness 10 thereby made adaptable to a player with a short torso.

The harness 10 is removed by unbuckling the buckles 48 and 92 and reversing the foregoing procedure.

What I claim is:

1. A combination hip and body harness which is adjustable to the torso length of a football player, comprising a padded hip protector adapted to snugly encircle the player's hips and fit against the back and sides thereof, means for firmly securing said hip protector around the player's hips against downward movement relatively thereto, an upstanding girdle-shaped rib-and-kidney protector adapted to loosely encircle the rib and kidney regions of the player's body in vertically-spaced relationship with said hip protector, and a plurality of upstanding self-sustaining rib-and-kidney protector supporting devices having their lower ends connected to and supportedly engaging the upper portion of said hip protector and having their upper ends connected to and supportingly engaging the lower portions of said rib-and-kidney protector, said rib-and-kidney protector extending upwardly from said supporting devices and having forwardly-disposed rib protector portions extending over the player's rib regions and rearwardly-disposed kidney protector portions extending over the player's kidney regions, each of said supporting devices including a vertical support and a vertically-extensible and retractable connector adjustably joining said support with one of said protectors.

2. A combination hip and body harness which is adjustable to the torso length of a football player, comprising a padded hip protector adapted to snugly encircle the player's hips and fit against the back and sides thereof, means for firmly securing said hip protector around the player's hips against downward movement relatively thereto, an upstanding girdle-shaped rib-and-kidney protector adapted to loosely encircle the rib and kidney regions of the player's body in vertically-spaced relationship with said hip protector, and a plurality of upstanding self-sustaining rib-and-kidney protector supporting devices having their lower ends connected to and supportedly engaging the upper portion of said hip protector and having their upper ends connected to and supportingly engaging the lower portions of said rib-and-kidney protector, said rib-and-kidney protector extending upwardly from said supporting devices and having forwardly-disposed rib protector portions extending over the player's rib regions and rearwardly-disposed kidney protector portions extending over the player's kidney regions, each of said supporting devices including a vertical support and a vertically-extensible and retractable flexible connector adjustably joining said support with one of said protectors.

3. A combination hip and body harness which is adjustable to the torso length of a football player, comprising a padded hip protector adapted to snugly encircle the player's hips and fit against the back and sides thereof, means for firmly securing said hip protector around the player's hips against downward movement relatively thereto, an upstanding girdle-shaped rib-and-kidney protector adapted to loosely encircle the rib and kidney regions of the player's body in vertically-spaced relationship with said hip protector, and a plurality of upstanding supporting devices having their lower ends connected to and supportedly engaging the upper portion of said hip protector and having their upper ends connected to and supportingly engaging the lower portions of said rib-and-kidney protector, said rib-and-kidney protector extending upwardly from said supporting devices and having forwardly-disposed rib protector portions extending over the player's rib regions and rearwardly-disposed kidney protector portions extending over the player's kidney regions, each of said devices including a vertical support and a vertically-extensible and retractable connector adjustably secured to each of the upper and lower end portions of said support and joining said support with both of said protectors.

4. A combination hip and body harness which is adjustable to the torso length of a football player, comprising a padded hip protector adapted to snugly encircle the player's hips and fit against the back and sides thereof, means for firmly securing said hip protector around the player's hips against downward movement relatively thereto, an upstanding girdle-shaped rib-and-kidney protector adapted to loosely encircle the rib and kidney regions of the player's body in vertically-spaced relationship with said hip protector, and a plurality of upstanding supporting devices having their lower ends connected to and supportedly engaging the upper portion of said hip protector and having their upper ends connected to and supportingly engaging the lower portions of said rib-and-kidney protector, said rib-and-kidney protector extending upwardly from said supporting devices and having forwardly-disposed rib protector portions extending over the player's rib regions and rearwardly-disposed kidney protector portions extending over the player's kidney regions, each of said devices including a vertical support and a vertically-extensible and retractable flexible connector adjustably secured to each of the upper and lower end portions of said support and joining said support with both of said protectors.

5. A combination hip and body harness which is adjustable to the torso length of a football player, comprising a padded hip protector adapted to snugly encircle the player's hips and fit against the back and sides thereof, means for firmly securing said hip protector around the player's hips against downward movement relatively thereto, an upstanding girdle-shaped rib-and-kidney protector adapted to loosely encircle the rib and kidney regions of the player's body in vertically-spaced relationship with said hip protector, and a plurality of upstanding self-sustaining rib-and-kidney protector supporting devices having their lower ends connected to and supportedly engaging the upper portion of said hip protector and having their upper ends connected to and supportingly engaging the lower portions of said rib-and-kidney protector, said rib-and-kidney protector extending upwardly from said supporting devices and having forwardly-disposed rib protector portions extending over the player's rib regions and rearwardly-disposed kidney protector portions extending over the player's kidney regions, each of said supporting devices including a vertical support and a vertically-extensible and retractable flexible connector adjustably joining said support with one of said protectors, said support having an opening, and said flexible connector being threaded around one end of said support and through said opening.

6. A combination hip and body harness which is adjustable to the torso length of a football player, com-

prising a padded hip protector adapted to snugly encircle the player's hips and fit against the back and sides thereof, means for firmly securing said hip protector around the player's hips against downward movement relatively thereto, a rib-and-kidney protector adapted to loosely encircle the rib and kidney regions of the player's body in vertically-spaced relationship with said hip protector, and a plurality of upstanding supporting devices having their lower ends connected to and supportedly engaging the upper portion of said hip protector and having their upper ends connected to and supportingly engaging the lower portions of said rib-and-kidney protector, each of said devices including a vertical support and a vertically-extensible and retractable connector adjustably secured to each of the upper and lower end portions of said support and joining said support with both of said protectors, said support having a pair of vertically-spaced openings and the flexible connectors being threaded around their respective opposite ends of said support and through their respective openings.

7. A combination hip and body harness which is adjustable to the torso length of a football player, comprising a padded hip protector adapted to snugly encircle the player's hips and fit against the back and sides thereof, means for firmly securing said hip protector around the player's hips against downward movement relatively thereto, a rib-and-kidney protector adapted to loosely encircle the rib and kidney regions of the player's body in vertically-spaced relationship with said hip protector, and a plurality of upstanding supporting devices having their lower ends connected to and supportedly engaging the upper portion of said hip protector and having their upper ends connected to and supportingly engaging the lower portions of said rib-and-kidney protector, each of said devices including a vertical support and a vertically-extensible and retractable connector adjustably secured to each of the upper and lower end portions of said support and joining said support with both of said protectors, said support having a pair of vertically-spaced openings and the flexible connectors being threaded around their respective opposite ends of said support and through their respective openings, said device also including a fastener interconnecting the opposite ends of the flexible connectors.

8. A combination hip and body harness which is adjustable to the torso length of a football player, comprising a padded hip protector adapted to snugly encircle the player's hips and fit against the back and sides thereof, means for firmly securing said hip protector around the player's hips against downward movement relatively thereto, a rib-and-kidney protector adapted to loosely encircle the rib and kidney regions of the player's body in vertically-spaced relationship with said hip protector, and a plurality of upstanding supporting devices having their lower ends connected to and supportedly engaging the upper portion of said hip protector and having their upper ends connected to and supportingly engaging the lower portions of said rib-and-kidney protector, each of said devices including a vertical support and a vertically-extensible and retractable connector adjustably secured to each of the upper and lower end portions of said support and joining said support with both of said protectors, said support having a pair of vertically-spaced openings and the flexible connectors being threaded around their respective opposite ends of said support and through their respective openings, said device also including an extensible and retractable fastener adjustably interconnecting the opposite ends of the flexible connectors.
